UNITED STATES PATENT OFFICE.

DAVID C. A. BOSWORTH, OF BROOKLYN, NEW YORK.

PHONOGRAPH ATTACHMENT.

1,414,687.

Specification of Letters Patent. Patented May 2, 1922.

Application filed May 4, 1920. Serial No. 378,931.

To all whom it may concern:

Be it known that I, DAVID C. A. BOSWORTH, a citizen of the United States, and a resident of New York city, borough of Brooklyn, in the county of Kings and State of New York, have made and invented certain new and useful Improvements in Phonograph Attachments, of which the following is a specification.

10 My invention relates to a winding mechanism for phonographs, which may be easily and readily attached to a phonograph regardless of its size or particular make, and will, efficiently and quickly rewind the phonograph motor when actuated by a direct pull upon a flexible member or tape.

I am aware that it has heretofore been proposed to provide a rewinding mechanism for a phonograph which is substituted for the ordinary crank handle and is operated by a direct pull upon a flexible member or tape. In all such devices, however, as heretofore constructed, it has been necessary to rigidly secure them to the cabinet of the phonograph and in so doing they become a permanent part thereof. This attachment of the winding mechanism to the phonograph requires the use of holding screws or other attaching means, which tends to mar and injure the cabinet. Further the attachment of the winding device has heretofore required the use of special tools and the employment of considerable skill and in addition has presented an unsightly appearance, being in discord with the regular and symmetrical lines of the usual phonograph cabinet.

It is accordingly an object of my invention to provide a rewinding mechanism, which may be easily and quickly secured to a phonograph, does not comprehend the use of holding screws or similar attaching means, and accordingly does not involve the marring or injuring of the cabinet. Further the rewinding mechanism is of simple and neat appearance, occupying but little space, and conforming to the symmetrical lines of the ordinary phonograph cabinet.

50 A further object is to provide a phonograph winder having the aforementioned characteristics, and which, in addition, is simple in construction, may be readily and economically manufactured, and capable of efficiently performing the service for which it is intended. Further the winding mecha-

nism embodies a minimum number of parts, so that the entire device will be rugged and durable in service.

With the foregoing and other objects in view, which will appear as the description proceeds, my invention resides in the novel phonograph rewinding mechanism, as herein described and illustrated and in the combination and arrangement of parts and in the details of construction hereinafter described and claimed wherein it is to be understood that changes may be made within the scope of the appended claims without departing from the spirit of my invention.

The preferred embodiment of my invention is disclosed in the accompanying drawings, wherein:

Figure 1 is a view in side elevation and partially in section of a phonograph equipped with my improved rewinding attachment;

Fig. 2 is a view in vertical section taken on the line 2—2 of Fig. 4;

Fig. 3 is a view in vertical section taken on the line 3—3 of Fig. 4;

Fig. 4 is a view in vertical longitudinal section of my improved rewinding attachment;

Fig. 5 is a view in vertical longitudinal section of my improved rewinding attachment having a slightly modified form of operating mechanism;

Fig. 6 is a view in vertical section taken on the line 6—6 of Fig. 5; and

Fig. 7 is a view in vertical section taken on the line 7—7 of Fig. 5.

Referring specifically to the several views wherein similar reference numerals designate corresponding parts throughout, my improved phonograph rewinding attachment is composed of a main circular casing 10, which is open at the front extremity and is provided with a cover 11. Housed within the casing 10 is a drum 12, to which is rigidly secured a bushing 13. The rear wall 14 of the casing is provided with an opening 15 therein, which rotatably receives the bushing 13 therethrough. A portion of the drum 12 is cut away as at 16, and receives a ratchet wheel 17 therein. A pawl 18 is pivotally secured to the drum 12, by the pin or other attaching means 19, the action of the pawl and ratchet wheel 17 being to allow the drum 12 to rotate freely in one direction independent of the ratchet

wheel, but to forcibly drive the ratchet wheel when rotating in the opposite direction.

A supplemental casing 20 is secured to the main casing 10, and houses therein the torsion spring 21. The bushing 13 of the drum projects through and is rotatably received by the opening 22 in the end wall of the supplemental casing 20. The spring 21 is connected at its one extremity to the bushing 13, and at its opposite extremity to the supplemental casing 20.

Extending through the bushing 13, and effecting a rotatable joint therewith is the winding shaft 23, the one extremity of which, as illustrated in Fig. 1, is secured to, so as to positively drive, the phonograph motor M. The winding shaft 23 projects through the opening in the side wall 24 of the phonograph cabinet and is provided adjacent its outer extremity with the rigidly attached ratchet wheel 17. Extending inwardly from the center of the cover of the casing is the pivot pin 25, which forms a bearing support for the front extremity of the winding shaft 23, the latter being provided with an opening 26 in which the bearing pin 25 fits and effects a rotatable junction. The winding shaft 23 is provided with the outstanding projections 27, thus affording means for manually turning the winding shaft in a reversed direction so that it may be disconnected from the phonograph motor M, and the attachment removed should it be so desired.

A washer or ring 28 is fixedly secured to the bushing 13, and holds it and the drum to which the same is connected in place during such time as the cover 11 is removed. The winding drum is preferably provided with a groove 29, which receives a flexible member or tape 30 therein, the same being composed of a metal strip 31, surrounded by a cloth covering 32. The protruding extremity of the flexible tape is provided with the handle 33. Suitable rollers 34 are situated adjacent the opening 35 in the casing and through which the flexible tape extends, thus preventing undue wear upon the tape.

With the parts as thus arranged when the handle 33 is firmly grasped and moved outwardly, it causes the rapid rotation of the drum 12, which is imparted to the winding shaft 23 by means of the pawl 18 and ratchet wheel 17, thus causing the winding or rewinding of the phonograph motor. At the same time, the spring 21 is wound or energized due to the relative rotation of the drum and the casing 10. The casing is prevented from rotating by the action of the tape bearing upon the roller 34. After the tape has been unwound, the handle 33 is moved inwardly, allowing the drum 12 to rapidly rewind the tape thereon, due to the

action of the spring 21; the casing remaining stationary during this operation due to the presence of the tape bearing upon the roller 34. In fact it has been found that should the handle be suddenly released after 70 having been drawn out to its furthest point, the weight of the handle will be sufficient to maintain the tape taut during this rewinding and thus hold the casing against rotation and in fact should the rotation of 75 the casing take place, rather than the reverse turning of the drum, the same effect will be had as the rotation of the casing would rewind the tape upon the drum and in so doing return the handle to its original and 80 retracted position. The casing, being supported solely by the shaft 23 and the shaft being adapted to rotate with respect to the casing, is allowed to assume a position wherein the flexible member when pulled 85 will assume a straight line and tangential to the drum upon which the flexible member is wound, so that the entire pull will be directly transmitted to the drum with the least 90 possible friction and regardless of the particular direction in which the handle is pulled.

In order to make the attachment of universal use, several of the winding shafts with the ratchet wheels thereon are provided and are of different lengths and provided with different end connections for the motor M, so that in supplying a customer with one of my improved winding attachments the size and style of phonograph is 100 first ascertained and then a shaft of proper length and construction provided and secured in place by first removing the cover 11 and inserting the winding shaft through the bushing 13, and then replacing the cover 105 substantially as shown in the drawings, a reversed procedure being used when for any reason it is desired to remove the winding attachment from a phonograph.

The somewhat modified form of construction illustrated in Figs. 5, 6, and 7, is modified only with regard to the construction of the several parts and operates in a precisely similar manner to that above outlined. Referring to the drawings in question, the drum 50 is preferably formed of stamped metal and composed of the web, rim and flange 51, and a second flange piece 52, is held to 51 by the ears 53, thus forming a light and economical wheel or drum. Secured to 115 the web is the bushing 54, which is rotatably mounted upon a sleeve 55, the latter being in turn rotatably mounted at its front extremity by the bearing 56, and at its rear extremity by the opening 57 in the rear wall 120 of the casing 58. Rigidly secured to the sleeve 55 and resting against the web of the drum 51 is the ratchet wheel 59, which through the action of the pawl 60 is adapted 125 to positively rotate the sleeve 55 upon the ro- 130

tation of the drum 51 in one direction, the reverse rotation of the drum taking place independent of the sleeve. The bushing 54 is extended so as to bear against the rear wall 5 of the casing 58, which feature together with the action of the ratchet wheel bearing against the web of the drum and the reception of the sleeve 55 within the bearing 56, holds the several parts against longitudinal 10 shifting.

In order that the rotation of the sleeve will effect the rotation of the winding shaft of the phonograph and in order that the said winding shaft may be of the proper length 15 and construction, so as to fit a certain or given type of phonograph, I have preferably provided the sleeve at its upper extremity with the reduced squared aperture 61, and in addition have provided the main 20 aperture 62 of the sleeve with a semi-circular groove 63, in which is contained a wire ring 64. The winding shaft 65 is provided at its outer extremity with the squared end 66 and with the semi-circular 25 grooves 67 adjacent the same. Thus when it is desired to supply a customer with my improved winding attachment, a winding shaft of the proper length and construction for the phonograph in question is selected, the original winding handle of the 30 phonograph removed and the winding shaft 65 secured in its place, the extremity of the winding shaft protruding through the side of the phonograph cabinet substantially as 35 shown in Fig. 5. The casing containing the various parts therein as previously described, is forcibly moved upon the winding shaft until the squared end of the shaft reposes in the squared extremity of the sleeve, 40 the wire ring in the sleeve engaging one of the grooves in the winding shaft and holding the casing securely in adjusted position. A flexible tape 68 having a handle 69 is provided and engages the drum 50 as previously 45 described. A torsion spring 70 is secured to the bushing 54 and to the casing 58 and provides for the retraction of the tape or flexible member after it has been forcibly drawn out during the winding op-

eration of the phonograph. A piece of felt 50 or other suitable material 71, is carried by the rear wall of the casing and prevents any marring or scarring of the side wall of the phonograph.

Having thus fully described my invention, what I claim is:—

1. A phonograph rewinding attachment comprising a shaft adapted to engage a phonograph motor, a casing engaging said shaft and solely supported thereby and adapted to turn with respect to said shaft and with respect to said phonograph, a flexible member, and means housed within said casing engaging said shaft and said casing and engaged by said flexible member and adapted to rotate said shaft as said flexible member is pulled outwardly for the rewinding of said phonograph motor, and to cause the free retraction of said flexible member, said means and the mounting of said casing adapted to allow the casing to turn with respect to the phonograph and to accommodate itself to the direction of pull upon the flexible member.

2. A phonograph rewinding attachment 75 comprising a casing, a winding drum therein, a torsional spring engaging said drum and said casing, a flexible member encircling said drum and protruding from said casing, a shaft adapted to engage a phonograph motor, means engaging said shaft and said drum adapted to cause the rotation of said shaft as said flexible member rotates the said drum during the unwinding thereof and adapted to allow the free reverse rotation of 80 said drum with respect to said shaft, and means whereby the shaft may engage and protrude at adjusted lengths from said casing.

Signed at New York borough of Manhattan, in the county of New York and State of New York this 28th day of April, 90 A. D. 1920.

DAVID C. A. BOSWORTH.
